US00D948644S

(12) **United States Design Patent** (10) **Patent No.:** **US D948,644 S**
(45) **Date of Patent:** **** Apr. 12, 2022**

(54) **EXERCISE TENSION BAR**

(71) Applicant: **T.K. Chin Company Ltd.**, Taipei (TW)

(72) Inventor: **Howard Chin**, Taipei (TW)

(73) Assignee: **T.K. Chin Company Ltd.**, Taipei (TW)

(**) Term: **15 Years**

(21) Appl. No.: **29/699,711**

(22) Filed: **Jul. 29, 2019**

(30) **Foreign Application Priority Data**

Jul. 10, 2019 (TW) 108124371

(51) **LOC (13) Cl.** **21-02**

(52) **U.S. Cl.**

USPC **D21/693**

(58) **Field of Classification Search**

(57) **CLAIM**

The ornamental design for an exercise tension bar, as shown.

DESCRIPTION

FIG. 1 is a perspective view of an exercise tension bar showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

1 Claim, 7 Drawing Sheets
